US0D1054528S

(12) **United States Design Patent** (10) Patent No.: **US D1,054,528 S**
(45) Date of Patent: ** Dec. 17, 2024

(54) **ROOT IRRIGATION SYSTEM**

(71) Applicant: **Robert G Summers**, Pasadena, CA (US)

(72) Inventor: **Robert G Summers**, Pasadena, CA (US)

(**) Term: **15 Years**

(21) Appl. No.: **29/810,901**

(22) Filed: **Oct. 8, 2021**

(51) LOC (14) Cl. **23-01**

(52) U.S. Cl.

USPC **D23/216**; D23/213; D23/214

Primary Examiner — Keith J Wilson

(57) **CLAIM**

The ornamental design for a root irrigation system, as shown and described.

DESCRIPTION

FIG. 1 is a perspective view of a root irrigation system; FIG. 2 is a top plan view of the root irrigation system; FIG. 3 is a bottom plan view of the root irrigation system; FIG. 4 is a front elevation view of the root irrigation system; FIG. 5 is a right elevation view of the root irrigation system; FIG. 6 is a rear elevation view of the root irrigation system; and, FIG. 7 is a left elevation view of the root irrigation system. Any of the phantom lines of FIGS. 1-7 are included for the purpose of illustration and forms no part of the claimed design.

1 Claim, 7 Drawing Sheets
